Primary Examiner — Karen S Acker(74) *Attorney, Agent, or Firm* — Bryan Cave Leighton
Paisner LLP(57) **CLAIM**

The ornamental design for a fabric with surface patterns, as
 shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top plan view of a fabric with surface pattern

according to a first embodiment; and,

FIG. 2 is a top plan view of a fabric with surface pattern
 according to a second embodiment.

1 Claim, 2 Drawing Sheets
(2 of 2 Drawing Sheet(s) Filed in Color)
